UNITED STATES PATENT OFFICE

115,775

DESIGN FOR A PHOTOGRAPHIC PRINTER

Carl F. Wolters, Kenmore, and Allan H. Tober,
Buffalo, N. Y., assignors to Remington Rand
Inc., Buffalo, N. Y.

Application May 4, 1939, Serial No. 84,798

Term of patent 7 years

To all whom it may concern:

Be it known that we, Carl F. Wolters and Allan H. Tober, citizens of the United States, residing at Kenmore and Buffalo, respectively, in the county of Erie and State of New York, have invented a new, original, and ornamental Design for a Photographic Printer, of which the following is a specification, reference being had to the accompanying drawing, forming part thereof,

The figure is a perspective view of a photographic printer, showing our new design.

We claim:

The ornamental design for a photographic printer, as shown.

CARL F. WOLTERS.
ALLAN H. TOBER.
